CONTAINER

Filed May 4, 1928

Inventor

Charles H. Hope
By Joseph A. Miller

Attorney

UNITED STATES PATENT OFFICE.

CHARLES H. HOPE, OF PROVIDENCE, RHODE ISLAND.

CONTAINER.

Application filed May 4, 1928. Serial No. 274,992.

This invention relates to certain new and useful improvements in containers, and pertains more particularly to a container used in the transportation or storage of copper 5 rolls employed in printing machines. These rolls have engraved or ornamented surfaces, and it is desirable to transport the rolls so as to maintain the engraved or ornamented surfaces or peripheries thereof, out of contact with the container, thereby to prevent 10 injury to or marring thereof, and the invention therefore aims to provide a container which will enable shipment or storage of the rolls with their peripheries out of contact with the container walls.

The invention further aims to provide a container of this type which is readily adjustable to rolls of varying lengths and to further provide means for locking the two 20 parts of the container against movement in adjusted position thereof.

The invention still further aims to provide a container which is of simple and economical construction and in which the 25 container may be rolled in handling thereof and without danger of marring or injuring the surface of the roll.

In the drawings:—

Figure 1 is an elevation of the invention; 30 Figure 2 is a longitudinal sectional view, and

Figure 3 is a section on line 3—3 of Figure 2.

In proceeding in accordance with the 35 present invention, a pair of hollow and preferably tubular or cylindrical members 1 and 2 are provided and which are telescopically related. The outer ends of the members are provided with heads 3 and 4 respectively, the latter having reduced annular portions 5 and 6 which are threaded into engagement with the members 1 and 2 the latter being preferably formed of fibrous material, while the heads are formed of metal. The heads have cone-shaped projections 7 and 8 respectively which are 45 adapted to engage with the ends of a copper printing roll R, which latter are of tubular construction. The inner end of the member 1 is longitudinally slotted as indicated at 9 and a clamping ring 10 is engaged about said end and has outwardly extending ears 11 perforated to receive a nut and bolt 12.

In operation, it will be noted that the 50 member 2 upon being removed enables the

roll R to be inserted in the member 1 with its inner end engaged with the cone 7 which latter centers the tube automatically, as is apparent from Figure 2. The member 2 is then inserted in the member 1 until its 60 cone 8 engages the opposite end of the roll R, and when the parts are so related, the nut of the bolt 12 is then tightened so as to clamp the inner end of the member 1 to the member 2 thereby preventing movement 65 of the parts. As clearly depicted in the drawings, the latching or locking element 10 is located wholly within the peripheries of the heads 3 and 4, consequently the container can be rolled on a surface in handling same. It will further be noted that the members 1 and 2 are readily adjustable, so as to thereby provide for the storage of rolls of varying lengths within the telescopic limits of the two members.

Having thus described my invention what I claim as new and desire to secure by Letters Patent is:—

1. In a container, a pair of telescopic members, a head for each member composed of a circular base having a reduced exteriorly threaded portion threadedly engaged with the interior of one end of the member and having a substantially cone-like portion projecting outwardly from the central part of the reduced portion, the outer of said members being split at its opposite end, and a clamp adjustably secured about said split end to clamp the latter to the inner member, the periphery of the bases of the heads extending outwardly beyond said clamp so as to allow of rolling of the container.

2. In a container, a pair of telescopic members, a head for each member composed of a circular base having a reduced exteriorly threaded portion threadedly engaged with the interior of one end of the member and having a substantially cone-like portion projecting outwardly from the central part of the reduced portion, the outer of said members being split at its opposite end, and means to detachably connect the opposite end of the outer member to the inner member so as to hold the members against relative movement.

3. In a container, a pair of telescopic members, a head for each member composed of a circular base having a reduced exteriorly threaded portion threadedly en-

gaged with the interior of one end of the member and having a substantially cone-like portion projecting outwardly from the central part of the reduced portion, the outer ⁵ of said members being split at its opposite end, and means to detachably connect the opposite end of the outer member to the

inner member so as to hold the members against relative movement, said means being disposed wholly within the peripheries of ¹⁰ the heads so as to allow of rolling thereof.

In testimony whereof I have signed my name to this specification.

CHARLES H. HOPE.
